UNITED STATES PATENT OFFICE.

JOSEPH W. BOWERSOX, OF LOUISVILLE, KENTUCKY, ASSIGNOR OF ONE-HALF TO
ALBERT W. MOORE, OF PITTSBURGE, PENNSYLVANIA.

MATTRESS-TUFTING MACHINE.

1,344,605.

Specification of Letters Patent. Patented June 22, 1920.

Application filed April 7, 1919. Serial No. 288,009.

To all whom it may concern:

Be it known that I, JOSEPH WALLACE BOWERSOX, a citizen of the United States, residing in the city of Louisville, county of 5 Jefferson, and State of Kentucky, have invented a new and useful Improvement in Mattress-Tufting Machines, of which the following is a specification.

This invention relates to mattress tufting 10 machines.

In mattress making, after a tick is stuffed with suitable material it is "tufted" at intervals to prevent the stuffing from shifting. Tufting is accomplished by means of 15 a long needle wherewith a cord, or twine, is drawn down through the mattress and then back up a spaced distance from the first strand. The free end is then knotted about the main strand, a leather disk or a 20 bunch of fibrous material such as cotton, is placed between the twine and the tick, top and bottom, to prevent the twine cutting through the tick, the twine drawn tight and secured to the loose end above the knot.

25 The twine is then severed close to the knot.

A machine for tufting mattresses has been devised, which is constructed along the lines of the well known sewing machine, having a table of sufficient extent to accommodate 30 a mattress, an overhanging arm on the end of which is a head, a presser bar associated with the head on the lower end of which is a foot adapted to be brought down upon the mattress, a needle bar reciprocally 35 mounted in a guide which is so associated with the head that it may be advanced and retracted laterally a spaced distance therefrom, and a hollow needle detachably connected to the needle bar. The needle is

40 long enough to reach through the thickest mattress which it is anticipated will be made, and come into operative association with knotting mechanism positioned below the table. When threaded, the twine passes 45 down within the needle and out through an eye near the lower end thereof, normally projecting a short distance therefrom. When the needle is forced down through the mattress, it carries the twine along with it, the projecting end thereof being seized 50 by a gripper, within the knotting mechanism, and held as the needle is withdrawn, the twine trailing behind it. When the needle reaches the highest point of its travel, the guide is advanced so that as the needle

again descends, it pierces the mattress a spaced distance from the first point. As the needle descends, suitable mechanism interposes a short piece of cotton wicking between the ticking and the descending bight 55 of twine. When the needle reaches the knot tying device a loop is formed in the twine, the end thereof released, drawn through the loop and again seized, and a knot formed. The needle then rises exerting tension on the twine, drawing the knot tight, in the meantime a short piece of wicking having been inserted between the knot and the ticking, to prevent the twine from cutting through the ticking. As the point of 60 the needle rises above the presser foot, mechanism associated therewith cuts the twine, after which the presser foot is raised, and the stuffing expands taking up any slack 65 in the twine. Immediately following the 70 cutting of the twine, the lower end thereof is released, the presser foot is then raised and the mattress may be shifted and the operation repeated. The apparatus as outlined above functions satisfactorily, but is 75 wasteful of twine. It is to be observed that as the knot lies against the underside of the mattress, a loose end of the twine extends up through the mattress and that another "tail end" extends down to the gripper in the tying mechanism. These tails are, to say the least, unsightly,—consequently after the tufting is completed, the mattress must be turned over and all of them 80 cut off manually, entailing thereby considerable labor.

An object of this invention is to provide means whereby the position of the knot may be shifted from the exterior of the mattress, adjacent the outer surface of a tick, to a 85 point interior thereof, adjacent the inner surface of the other tick, with the result that the twine will be severed close to the knot thereby effecting a saving of the length of twine that extends through the mattress, 90 at the same time drawing the tail end of the twine into the interior of the mattress whereby the need for cutting it off is eliminated.

More specific objects, features and advantages will more clearly appear from the detailed description given below, taken in connection with the accompanying drawing, wherein—Figure 1, is a side elevation of such portions of a mattress tufting machine 100

- as is necessary to a clear understanding of the application of an embodiment of my invention thereto: Fig. 2, a front elevation of the gripper device: Fig. 3, a side elevation 5 of the gripper: Fig. 4, a top plan view of the gripper and its actuating cam, the immediate associated parts of the machine being shown in section: Fig. 5, a perspective view of the cam and its attaching plate: Fig. 6, a vertical section through a mattress 10 in proximity to a tuft showing the location of the knot before being shifted into the mattress: Fig. 7, a view similar to Fig. 6, showing the location of a knot according to 15 my invention.

Like parts in the several views are designated by corresponding reference characters.

- Referring to the drawings the reference character —1— designates the table of a 20 mattress tufting machine, which is adapted to support a mattress —2— to be tufted, beneath which an inclosure, or box —3— is positioned which houses suitable mechanism for tying a knot, which is actuated by 25 means of a shaft —4—. As the knot tying mechanism forms no part of, and a knowledge of its operation is not essential to an understanding of the present invention, no description thereof is considered necessary. 30 On the end of an overhanging arm —6— is a head —7— associated with which is a vertically movable presser bar —8— affixed to the lower end of which is a foot —9— which is adapted to be brought down 35 upon a mattress to compress it locally and to hold it against shifting during the operation of tufting. This bar is raised and lowered by suitable means such as a lever —10—. Associated with the head is a 40 needle bar guide —11— in which a needle bar —12— is slidably mounted, being actuated by means of a lever —13—. The guide is connected with the head by means of arms —14— which permit of its being advanced 45 laterally therefrom by means of a tapering or wedge shaped bar —15—, positioned between it and the presser bar, which is raised and lowered by means of a lever —16—. The guide is retracted by suitable means 50 such as a spring —18—. A needle —17— affixed to the lower end of the needle bar, is of sufficient length to extend through the mattress and present the twine, which it carries, to the knot tying mechanism contained in the box 3. Gripping mechanism, 55 designated as an entirety by the numeral —20— is affixed to the needle bar and travels down and up therewith. It comprises a rectangular base —21— having 60 a rib —22— on its side, adapted to be fitted in a slot —23— in the guide bar and provided with perforations —24— for the passage of screws wherewith it may be secured to the needle bar. A wall —25— 65 erected at one side of and perpendicular to

the base, carries on its outer edge, a bridge plate —26— which extends over the base. A stem —27— is slidably mounted in aligned openings in the bridge and the base. A pair of friction disks —30, 31— are loosely 70 mounted upon the stem and a coiled spring —32— disposed about the stem, bears respectively against the outer disk and a collar —33— on the stem, the collar in turn bearing against the bridge. A lever —35— 75 having a straight arm —36— and a curved arm —37— is pivotally attached at —38— to the outerside of the wall 25. A lateral extension —39— from the curved arm 37, terminates over the end of the stem. The 80 arrangement being such that actuation of the lever 35 in one direction will cause a depression of the stem thereby compressing the spring and increasing the pressure between the disks. A friction roller —40— 85 is mounted on the end of the arm 36, and a spring —41— serves to normally maintain the arm 39 in contact with the end of the stem. A plate —45— laterally adjustable relative thereto is attached to the head 90 7, and a cam bar —46— vertically adjustable relative thereto is positioned on the plate parallel with the face of the head and in such position that it will lie in the path of the roller 40, when the needle bar guide and associated elements, is advanced from the head. In threading the machine, the twine, or thread —49—, is lead from a spool —50— through a guide —51— on the upper end of the needle bar, about a pin —42—, 100 between the disks 30, 31 about a pin —44— down through the needle and out a side opening near the lower end thereof. In operation, a mattress being positioned, on the table, the presser foot is brought down 105 upon it and the needle forced down therethrough, carrying the twine with it, the end of the twine protruding from the needle is seized and held, by an element of the knotting mechanism. The needle is then withdrawn paying out the twine, a section —52— thereof remaining permanently within the mattress. As the needle reaches the upper limit of its movement, the lever 16, depresses the bar 15, forcing the needle 110 bar guide outward (Fig. 1) a spaced distance from the head, and the needle again descends. As the needle bar goes down the roller 40 contacts with the curved upper end —53— of the cam bar 46, and the arm 115 36 is deflected inward against the pressure of the spring 41, which restores it to a normal position after the bar is passed. In this descent the needle pierces the mattress a spaced distance from the first puncture and carries with it a section —54— of twine. When this section of twine is brought into operative relationship with the knotting mechanism, a knot —55— is formed 120 uniting the two sections. In the meantime 125 130

- suitable means have interposed short sections —56, 57— of cotton wicking between the twine and the ticking. The needle then rises leaving a third section —58— of twine 5 within the mattress. (Fig. 6). Just after the needle starts upward, the roller 40 contacts with the curved lower end of the cam bar and the lever 35 is actuated to compress the spring 32 exerting such a pressure upon 10 the disks 30, 31, that the twine held therebetween is firmly gripped at the same time the knotting mechanism releases the end of the twine held therein, and the continued upward movement of the needle bar pulls the 15 knot, and the tail end —59— through the lower tick and up through the mattress against the inner surface of the upper tick. At this moment the roller 40, reaches the upper end of the cam bar, and escapes 20 therefrom releasing the pressure on the twine and the needle completes its upward movement. The twine is then severed, by suitable means, in proximity to the presser foot, the presser foot raised and the mattress may be shifted to make another tuft. 25 It is to be understood that the mechanism is so constructed and timed that the movements described occur sequentially without further attention of the operator other than 30 to operate a foot pedal to start the machine and to shift the mattress. It will be observed that by shifting the knot, to the interior of the mattress, drawing the section 58 thereout of a saving of twine is effected 35 on every tuft, equal to the thickness of the mattress, and that drawing the tail end 59 into the mattress obviates the necessity of cutting it off whereby quite a saving in material and labor is effected.
- 40 While I have described my improvement in great detail, and with respect to one form thereof, I do not desire to be limited to such details, as many changes and modifications may well be made without departing from the spirit and scope of the invention especially in its broader aspects. Hence I desire to cover all arrangements and modifications coming within the language of the appended claims.
- 50 Having thus described my invention so that anyone skilled in the art pertaining thereto can make and use the same,
- I claim:
1. The method of tufting a mattress, consisting in passing the branches of a looped thread through a mattress in spaced parallel relationship, knotting the protruding ends thereof together and pulling said knot through the ticking into the interior of the 55 mattress.
  2. In a mattress tufting machine, in combination with elements adapted to pass a thread through a mattress and tie a knot in 60 the same exterior of the mattress, means for shifting said knot to the interior of the 65 mattress.
  3. In a mattress tufting machine, in combination with elements adapted to pass the parallel spaced branches of a looped thread through a mattress and knot the protruding 70 ends thereof, means for drawing the knot within the mattress.
  4. In a mattress tufting machine, provided with elements adapted to pass parallel spaced branches of a looped thread 75 through a mattress and knot the protruding ends thereof together, means associated with one of said elements adapted to seize the thread and pull said knot through the mattress tick into the interior of the mat- 80 tress.
  5. In a mattress tufting machine provided with a reciprocal element adapted to pass strands of thread through a mattress and having means adapted to knot the 85 strands together on the far side of the mattress, gripping mechanism positioned on said element, a cam on a fixed portion of the machine adapted to actuate said mechanism to grip the thread whereby continued move- 90 ment of the element will pull the knot through the tick into the interior of the mattress.
  6. In a mattress tufting machine, a fixed member and a reciprocable element, a cam 95 on said member, gripping mechanism on said element, said gripping mechanism comprising a base, a wall perpendicular to said base, a bridge extended from said wall, said bridge and the base having alined perforations, a stem slidably positioned in said perforations, pressure disks loosely positioned on said stem, a collar on the stem normally bearing against the inner side of the bridge, a coil spring disposed about the 100 stem and bearing respectively against said collar and the outer disk, and a lever, one end of which bears upon the end of the stem and the other is adapted to be brought into the path of said cam by lateral move- 105 ment of the element.
  7. A gripper comprising a base, a wall perpendicular to said base, a bridge extended from said wall, said bridge and the base having alined perforations, a stem slidably positioned in said perforations, pressure disks loosely positioned on said stem, a collar on the stem normally bearing against the inner side of the bridge, a coil spring disposed about the stem and bearing 110 respectively against said collar and the outer disk, and a lever, one end of which bears upon the end of the stem and a roller 115 on the other adapted to contact with an actuating cam.

JOSEPH W. BOWERSOX.
